Primary Examiner—Charles Rademaker*(74) Attorney, Agent, or Firm*—Akin Gump Strauss Hauer & Feld LLP(57) **CLAIM**

The ornamental design for a vertebral defect device, as shown and described.

DESCRIPTION

FIG. 1 is a perspective view of a vertebral defect device showing my new design;

FIG. 2 is a left side elevation thereof;

FIG. 3 is a right side elevation thereof;

FIG. 4 is a bottom plan thereof;

FIG. 5 is a top plan view thereof;

FIG. 6 is a rear elevation thereof; and,

FIG. 7 is a front elevation thereof.

The broken lines in the figures are for illustrative purposes only and form no part of the claimed design.
